United States Patent Office

Des. 216,519
Patented Jan. 27, 1970

216,519

COMBINED SLIDE PROJECTOR AND COVER
Thomas M. Steinbach, Park Ridge, and Robert M.
Simonelli, Des Plaines, Ill., assignors to GAF
Corporation, New York, N.Y., a corporation of
Delaware

Filed Feb. 20, 1968, Ser. No. 10,654

Term of patent 14 years

Int. Cl. D16—03

U.S. Cl. D61—1

FIG - 2 -

FIG - 3 -

FIG. 5.FIG. 4.

FIG. 1 is a perspective view showing the top, front and left side of the combined side projector and cover embodying our new design;

FIG. 2 is a front elevational view thereof;

FIG. 3 is a rear elevational view thereof;

FIG. 4 is a left side elevational view thereof, the other side being substantially a mirror image of the side shown; and

FIG. 5 is a top plan view thereof.

The slide projector portion shown in phantom lines is for illustrative purposes only; the dominant portion of our design is shown in full lines.

We claim:

The ornamental design for a combined slide projector and cover, substantially as shown.
